UNITED STATES PATENT OFFICE.

ARTHUR M. HOOD, OF INDIANAPOLIS, INDIANA.

SLACK-LINE EXCAVATOR.

Application filed December 27, 1923. Serial No. 682,921.

To all whom it may concern:

Be it known that I, ARTHUR M. HOOD, a citizen of the United States, residing at Indianapolis, in the county of Marion and 5 State of Indiana, have invented a new and useful Slack-Line Excavator, of which the following is a specification.

The object of my invention is to provide certain improvements in construction of a 10 scraper bucket type of excavator, commonly known as a slack line excavator, by means of which material may be excavated at one point and dumped at another. The accompanying drawings illustrate my invention.

15 Fig. 1 is a side elevation of an embodiment of my invention; Fig. 2 a plan of the carriage and supporting track cable; Fig. 3 a front elevation of the carriage, and Fig. 4 a fragmentary vertical section with 20 the parts in position as shown immediately preceding gravity dumping action.

In the drawings 10 indicates a track cable upon which the apparatus is most conveniently mounted and operated, said 25 track cable being generally arranged with its lower end attached to a "dead man" and its upper end attached to a suitable block and tackle by which the track cable may be conveniently slackened and tautened, 30 this construction being common and well-known in the art.

Movably mounted upon and along the track cable is a carriage 11 from which is suspended, by means of the suspension member 12, a forwardly unbalanced scraper bucket 13.

40 Located in the lower forward portion of carriage 11 is a double idler 14 composed of two slightly spaced portions each having a chain supported peripheral 14', the two 45 parts being so arranged that the lifting chain 15 may ride thereon without entering the space 16 between the two portions of idler 14, to normally support the forwardly unbalanced weight of bucket 13.

As a part of chain 15 I provide a long link 17 the thickness of which is such as to permit its entry into the space 16, the 50 points of attachment 17' and 17'' between the upper and lower portions of chain 15, respectively, and link 17, and the link, being so proportioned that, when the parts are drawn to the position shown in Fig. 1, the point of attachment 17' will be at the 55 periphery 14', link 17 will lie within space 16, and the point of attachment 17'' effec-

tively nearer the axis of idler 14 than is the point of attachment 17''. Preferably these proportions are such that the point 60 17' will be in advance of the vertical plane of the axis of idler 14 and the point of attachment 17'' will be either directly beneath or slightly in advance thereof, in which latter case the unbalanced weight of the bucket and its load will have no tendency 65 to move the link 17 rearwardly.

The upper end of link 17, when the parts are in load-carrying position, lies immediately to the rear of a plunger 40 which is longitudinally slidable in carriage 11 and 70 projected somewhat in advance thereof so that it may be brought into engagement with a stop block 23 attached to the track cable 10 at any desired point of dump. A dragline 35 is bifurcated at 36 and extended to 75 the forward end of the bucket, and a movement of carriage 11 along the track cable, is controlled by a dragline.

The lift line 15 is connected to the dragline, conveniently at the bifurcation 36, the 80 parts being so proportioned that, when a transporting forward pull is exerted upon the dragline 35 the parts will be drawn to the position shown in full lines where the link 17, lying in the space 16, will largely 85 decrease, or preferably, temporarily wholly eliminate the efficiency of the unbalanced weight tending to cause a rearward movement of the lift line 15 and a consequent dumping of the load.

90 The operation is as follows:

Upon release of pull upon the dragline, the carriage and its supported bucket will run down the inclined track cable 10 to the point of desired excavation, the track cable being 95 appropriately slacked for that purpose.

Forward pull upon the dragline will cause a 100 lifting of the scraper bucket, and when the track cable is tautened, with an accompanying forward stress upon the dragline, link 17 and its associated parts will be brought to the position, relative to the carriage, shown in Fig. 1, and the loaded bucket will be 105 transported along the track cable. Just before, or just as, plunger 40 is brought into engagement with stop block 23, forward pull upon the dragline will be quickly discontinued so that the carriage, under its momentum, may continue its forward movement so that there may be a rearward movement of plunger 40 relative to the carriage, 110 to engage link 17 and kick it backwardly.

to the position shown in Fig. 4 where the unbalanced load of the bucket will become effective to draw the upper portion of the lift line 15 rearwardly over idler 14, and thus 5 permit the forward end of the bucket to swing downwardly and dump its load.

The slackening off of the dragline will, of course, after carriage 11 has come to rest, permit the carriage to move backwardly 10 down along the inclined track cable under the action of gravity, but this rearward movement of the carriage does not begin until after the unbalanced bucket has started to swing downwardly so that the dumping 15 of the load is not interfered with, although the dumped material is distributed, for some distance, in a rearward direction, due to the concurrent rearward movement of the carriage.

20 While some degree of skill is required of the operator in the manipulation of this device, that skill is quite readily attained, and if desired, in order to cushion the shock, the stop block 23 may embody a cushioning 25 spring 41.

I claim as my invention:

1. An excavator of the type described comprising, a carriage, a forwardly unbalanced scraper bucket pivotally supported on said 20 carriage, a dragline connected to the forward end of the bucket, a lift line connected to the forward end of the bucket, and passed over a support on the carriage to the dragline, means for decreasing the 25 bucket-dumping effectiveness of the forwardly unbalanced weight of the bucket, and means movably mounted on the carriage and adapted to co-operate with a stop member and the lift line as a result of forward movement of the carriage toward the stop to increase the bucket-dumping effectiveness of the forwardly unbalanced weight of the bucket.

2. An excavator of the type described comprising, a carriage, a forwardly unbalanced scraper bucket pivotally supported on said carriage, a dragline connected to the forward end of said bucket, a lift line connected to said dragline and extended back over a 45 support on the carriage and thence downwardly to the forward end of the bucket, the said lift line and its carriage support being of such character that, when the lift line has lifted the bucket to load-carrying posi-

tion, the effectiveness of the unbalanced 55 weight of the bucket tending to cause rearward movement of the lift line is less than it is just before the bucket reaches load-carrying position, and means movably mounted on the carriage and adapted to co-operate with a stop for acting upon the lift line, as a result of continued forward movement of the carriage relative to the stop, for increasing the bucket-dumping effectiveness of the forwardly unbalanced weight of the bucket. 60

3. An excavator of the type described, comprising, a carriage, a forwardly unbalanced scraper bucket pivotally supported on said carriage, a dragline connected to the forward end of the bucket, a lift line connected to the dragline and extended back over a support on the carriage and thence downwardly to the forward end of the bucket, said chain comprising a link 17 and the support formed to permit the link to 70 move to a position closer to the axis of the support than is permitted the adjacent advance portion of the chain, and means controlled by continued forward movement of the carriage on its support for positively shifting said link rearwardly relatively to its carriage support. 75

4. An excavator of the type described comprising, a carriage, a forwardly unbalanced scraper bucket pivotally supported on said carriage, a dragline connected to the forward end of the bucket, a lift line connected to the dragline and extended back over a support on the carriage and thence downwardly to the forward end of the bucket, said chain comprising a link 17 and the support formed to permit the link to move to a position closer to the axis of the support than is permitted the adjacent advance portion of the chain, and a plunger 80 longitudinally shiftable on said carriage, said plunger having a portion engaging the lift line and a portion projected forwardly of the carriage to engage a stop whereby continued forward movement of the carriage 85 relative to the plunger will cause said plunger to shift the link of the lift line rearwardly relative to its carriage support. 90

In witness whereof, I, ARTHUR M. HOOD have hereunto set my hand at Chicago, Illinois, this 25th day of December, A. D. one thousand nine hundred and twenty-three.

ARTHUR M. HOOD.
